US00D854027S

(12) **United States Design Patent** (10) **Patent No.:** **US D854,027 S**
Rasmussen et al. (45) **Date of Patent:** **** Jul. 16, 2019**

(54) **PORTION OF A DISPLAY PANEL WITH A GRAPHICAL USER INTERFACE WITH ICONS**

(71) Applicant: **Google Inc.**, Mountain View, CA (US)

(72) Inventors: **Johanne Bruun Rasmussen**, Aarhus (DK); **Steffen Christiansen**, New York, NY (US); **Jeppe Aaen**, Aarhus (DK)

(73) Assignee: **GOOGLE LLC**, Mountain View, CA (US)

(**) Term: **15 Years**

(21) Appl. No.: **29/606,146**

(22) Filed: **Jun. 1, 2017**

Related U.S. Application Data

(62) Division of application No. 29/518,259, filed on Feb. 20, 2015, now Pat. No. Des. 791,784.

CLAIM

The ornamental design for a portion of a display panel with a graphical user interface with icons, as shown and described.

DESCRIPTION

The FIGURE is a front view of a portion of a display panel with a graphical user interface with icons showing our new design.

The broken lines illustrate portions of the graphical user interface and form no part of the claimed design. The outermost rectangular perimeter illustrates a display screen portion.
